UNITED STATES PATENT OFFICE.

CLAIR G. HOOVER, OF AKRON, OHIO, ASSIGNOR TO THE GOODYEAR TIRE & RUBBER COMPANY, OF AKRON, OHIO, A CORPORATION OF OHIO.

APPARATUS FOR CEMENTING STRANDS OF CORDS.

1,251,032.

Specification of Letters Patent. Patented Dec. 25, 1917.

Application filed August 28, 1916. Serial No. 117,223.

To all whom it may concern:

Be it known that I, CLAIR G. HOOVER, a citizen of the United States, residing at Akron, in the county of Summit and State 5 of Ohio, have invented new and useful Improvements in Apparatus for Cementing Strands of Cords, of which the following is a specification.

My present invention relates to an apparatus for applying liquid coatings to cords, and in particular relates to a cementing apparatus whereby the individual strands composing a cord may be momentarily untwisted, coated and twisted again during the passing 15 sage of the cord through the apparatus.

As a principal object of my invention, I contemplate the provision of means for leading a continuous cord through a cement bath, and the provision of an instrument arranged 20 for a continuous rotational, progressive movement along the cord, said instrument serving to untwist the cord while the latter is yet in the cement bath and to twist the several strands of the cord together 25 after each strand has been individually coated and dried, or cooled, as the case may be.

It is also an object of this invention to arrange spreader means for untwisting a cord within a bath of liquid, with which it 30 is desired to coat the separate strands of the cord, in combination with a drying means adapted to dry the coatings upon the strands as the latter emerge from the bath prior to being retwisted into the cord form.

35 A further object of my invention is to provide means for moving the cords vertically through a cement bath; and to provide an untwisting and twisting device which is rotationally progressive along the length of 40 the cord and which is automatically actuatable by weight means to perform its offices in the process of coating the cord.

The above and additional objects of a similar nature, which will be hereinafter 45 more specifically treated, may be accomplished by such means as are illustrated in the accompanying drawings, described in the following specifications and then more particularly pointed out in the claims which 50 are appended hereto and form a part of this application.

With reference to the drawing, wherein there has been illustrated a preferred embodiment of the invention as it is reduced 55 to practice, the figure illustrates a vertical

section taken through the coating apparatus comprehended by my invention.

In the manufacture of cord ties and of fabric of various descriptions, it is frequently a desideratum to provide means 60 whereby the strands composing the cords of the tire or fabric be prevented from chafing against each other, as internal friction of this character is highly destructive. Since the old method of passing the cord bodily 65 through a bath of fluid rubber cement or some other non-fibrous, viscous and generally elastic material, does not effect a sufficient penetration of the cord to provide a uniform coating for each of the separate 70 strands composing the cords, I have had recourse to the method of momentarily untwisting the cord for the individual coating of each strand.

In carrying out my invention to attain the 75 objects set forth in the foregoing, an open receptacle 5 of a suitable depth is filled with the rubber cement or other fluid 6 with which it is desired to coat the cord.

Upon bearings 7 carried in alinement on 80 opposite sides of the tank, or receptacle 5, is supported a reel 8 whereon a quantity of cord 9 is wound. A braking means is provided to secure an even unwinding of the cord reel. This brake may consist of a flexible element 10 which supports a weight 11 and passes over the wound up cord to a point of securement 12, which may be upon a cross bar 13 straddling the sides of the tank 5. It is, of course, understood that a 85 hub and band brake for the end of the axle of reel 8 or any other equivalent means may be substituted for the braking means herein shown. The cord 9 is taken off the reel and trained over a small pulley 14 suitably secured as at 15 to the bottom of the coating tank, being thus given a preliminary exterior coating. It is then carried vertically 90 through the liquid 6 and over a pulley 16 which may be mounted upon a shaft 17 having bearings 18 at the sides of the tank. From this last turning point the cord is 95 withdrawn from the coating apparatus and wound up for subsequent use when desired.

Upon the cord portion between the pulleys 14 and 16 there is arranged the gravitational spreader device 19 which consists of a pair of cages 20 and 21 joined in vertical alinement by a rod 22. Each of the cages consists of a pair of plates 23 main- 100

110

tained in spaced relation by spindles 24. Projecting from the center rod 22 and immediately above the cage 20 are a number of spreader arms 25 making equal angles with 5 each other and being equal to the number of strands composing the cord 9. Each of these arms is bifurcated at its outermost extremity in order to mount a pulley 26 over which a single strand of the cord 9 may be trained 10 when the several cord strands are spread to suspend the device 19. A weight 27 is carried upon the center rod 22 to form the means of actuating the suspended spreader device. 15 In practice the end of the cord 9 is unraveled for a considerable distance after it has been introduced into the lower cage 20 of the spreader through a suitable aperture in the lowermost plate 23 of this cage. The 20 unraveled strands branch out from the cage center and are separately passed over their respective spreader arm pulleys 26, to converge toward the center of the upper cage 21, at which point they are retwisted into 25 their cord formation, the retwisted end of the cord being then carried through the apertured top plate 23 and over the upper pulley 16. When a pull is then exerted upon the cord end in the direction of the arrow 30 shown in the drawing, the spreader device 19 is lifted with the cord and then, owing to the action of the weight 27, begins a rotationally-progressive movement downward along the cord, screw-fashion. This movement 35 causes the untwisting of the cord within the cage 20 and also effects the retwisting of the cord within the cage 21, the separate strands being meanwhile independently coated during their upward passage through 40 the liquid within the tank 5. A guide arm 28 is secured to the side of the tank and projects outwardly into the path of travel of the cord after leaving the device 19, being apertured to permit the retwisted cord to 45 pass therethrough. This guide arm also acts as a stop to prevent a swift pull upon the cord 9 from lifting the device 19 completely out of the coating liquid 6. In actual use the pull upon the cord, which may 50 be gained by winding the cord upon a reel (not shown) to the right of the figure, should be at such a rate and of such uniformity as to maintain the device 19 at substantially a constant level within the liquid 55 6. Since it is imperative that the coated strands be at least partially dried before being retwisted into the cord formation, I may resort to either the use of an elongated rod 22, whereby the cages 20 and 21 are spaced a sufficient distance to allow for the natural air drying of the strands, or to the use of an air blast produced by a fan such as is denoted by the numeral 29, having a casing, the spout 30 of which projects

into close proximity to the cord to discharge a current of warm air thereagainst immediately after their emersion from the coating liquid 6.

It is known to me that Patents 874,287 70 and 85,219 to E. D. C. Bayne and L. A. Subers propose a method for momentarily untwisting successive portions of a cord length in order to apply a coating independently to the component strands of the 75 cord.

My present invention is, however, an improvement over the disclosures of these patents in a number of points. The Bayne and Subers device requires mechanical propulsion for their twisting and untwisting device which complicates their constructions and renders them more costly and less automatic than the weight operating means herein disclosed. Moreover, their container 4 80 for the coating liquid must necessarily have its bottom apertured to permit the passage of the cords therethrough which renders the cord passages liable both to blocking by hardened globules of the cement or to a leakage of the cement from its container. Also, the cords are not, in the mentioned patents, rotated in a surrounding body of cement which I have found to be advantageous for securing a full coating. Again my invention 85 is much more readily put into use since the individual strands do not have to be threaded through a number of apertures as is necessary in the devices of Bayne, *et al.* Simplicity, ease of operation, increased efficiency of results and cheapness are the advantages which render my invention an 90 improvement over these patents. 95

What I claim is:

1. In a cord coating apparatus, a container for a bath of a coating liquid; means to move the cord through said bath and an instrument suspended by the cord for momentarily resolving successive cord portions 105 into their strand components for individual coating within the bath.

2. In a cord coating apparatus, a container for a bath of a coating liquid; means for moving a cord through said bath and an instrument suspended upon the cord by the 110 individual strands thereof for momentarily untwisting the strands of the cord within the bath and for simultaneously retwisting the strands of the preceding cord portion 115 into a twisted cord formation upon emersion from the bath.

3. In a cord coating apparatus, a container for a bath of a coating liquid; means for passing a cord through said bath; and means gravitationally operable to resolve 125 successive cord portions continuously into their strand components while immersed within said bath.

4. In a cord coating apparatus, a container for a bath of a coating liquid; means 130

- for continuously passing a cord through said bath; and means suspended by the cord and capable of a continuous rotational and progressive movement therealong to untwist the 5 strands of the cord within the bath to expose them for individual coatings.
5. In a cord coating apparatus, a container for a bath of a coating liquid; means for continuously moving a cord through said 10 bath and gravitationally operable means suspended by the cord and capable of a continuous rotational and progressive movement along the length of the cord to resolve the 15 bath, whereby each strand of the cord is exposed for an individual coating.
6. In a cord coating apparatus, a container for a bath of a coating liquid; means for continuously moving a cord through said 20 bath; and means suspended by the cord and rotationally progressive therealong to untwist the strands of the cord within the bath and to retwist the strands into the cord formation exterior to the bath, after they have 25 been individually coated and dried.
7. In a cord coating apparatus, a container for a bath of a coating liquid; means for moving the cord through said bath to exit therefrom in a substantially vertical 30 part; and means for separating the strands of the cord while within the bath and for retwisting them into the cord formation exterior to the bath, said means being suspended by the cord and being automatically 35 operable upon the substantially vertical portion thereof.
8. In a cord coating apparatus, a container for a bath of a coating liquid; means for moving a cord through said bath; and
- means adapted to be suspended by the 40 strands of the cord when the latter are spread from the cord formation within the bath and subsequently retwisted in the cord formation exterior to the bath, said means being gravitationally operable to maintain 45 a rotational progressive movement along the cord in untwisting successive cord portions within the bath and continuously retwisting them again into the cord formation exteriorly from the bath. 50
9. In a cord coating apparatus, a container for a bath containing a coating fluid; means for the passing of cord continuously through the bath and an untwisting device suspended by said cord, said device including 55 spreader arms arranged to engage a separate individual strand of the cord in order to expose each strand for an independent coating within said bath.
10. In a cord coating apparatus, a container for a bath containing a coating fluid; means for continuously passing a cord through the fluid of said bath; a spreading device suspended by the cord and including spaced upper and lower cages; spreader arms 60 arranged adjacent to the lower cage to individually receive the separate strands of the cord branching out from the lower cage and to maintain them separate until within the upper cage, whereby the strands of the 70 cord are independently coated.

In testimony whereof I have signed my name in the presence of two subscribing witnesses.
